RADIO TUNER

Leslie R. Schroeder, Chicago, Ill., assignor to Warwick Manufacturing Corporation, a corporation of Delaware

Application January 27, 1955, Serial No. 484,337

11 Claims. (Cl. 74—10.7)

This invention relates to a belt-driven mechanism and, more particularly, to improved manual tuning means in a radio tuner also having push button tuning.

In normal practice, a radio tuner having both manual tuning and push button tuning has a rotatable operating shaft which mounts or at least drives the tuning condensers. This shaft has a releasable clutch thereon through which a driven shaft having a driven pulley at the driven end drives the operating shaft to effect manual tuning. In push button tuning, the clutch is disengaged to permit rotation of the operating shaft independently of the manual drive. This requires that the manual tuning driven shaft have a floating mounting and that the driven pulley and of said shaft be biased to maintain tension on a driving belt associated therewith.

An object of this invention is to provide a new and improved radio tuner.

Another object of this invention is to provide a radio tuner having a floating support for the driven pulley end of the manual tuning driven shaft and tensioning means which functions to maintain tension on the driving belt uniform for both directions of rotation of the driven pulley.

Another object is to floatingly support the pulley end of the driven shaft in a manner permitting limited angular displacement of the axis of the driven shaft while guiding the pulley end of the driven shaft for limited lateral displacement in a fixed line passing through the center line of the driven shaft and the center line of a control shaft carrying a manual tuning knob.

A further object of the invention is to provide a radio tuner having a manual control shaft with a pulley, a rotatable operating shaft which mounts or drives the tuning condensers and which has a releasable clutch thereon which may be disengaged when it is desired to adjust the tuning condensers by means of push button control and wherein in manual tuning a driven shaft disposed parallel to the control shaft is provided for moving the rotatable shaft through said clutch, the driven end of said driven shaft having a pulley engageable by an endless driving belt, said driven shaft being floatingly mounted by means of an elongated bar having laterally projecting fingers which form a ball and socket connection with a ball-shaped end of said driven shaft disposed within said pulley, the bar being mounted to the tuner frame for sliding movement along the center line of the belt which coincides with a line passing through the axes of said control and driven shafts, and spring means disposed along said center line urging the bar and pulley end of the driven shaft in a direction to maintain tension on the driving belt.

The objects of the invention, generally set forth, together with another ancillary advantages, are attained by the construction and arrangement shown by way of illustration in the accompanying drawing, in which:

Fig. 1 is a plan view of the radio tuner;

Fig. 2 is a front elevation of the radio tuner;

Fig. 3 is a side elevation of the radio tuner looking

toward the right hand side of the tuner, as shown in Fig. 2;

Fig. 4 is a section taken along the line 4—4 in Fig. 2;

Fig. 5 is a section taken along the line 5—5 in Fig. 2.

While this invention is susceptible of embodiment in many different forms, there is shown in the drawings and will herein be described in detail an illustrative embodiment of the invention with the understanding that the present disclosure is to be considered as an exemplification of the principles of the invention and is not intended to limit the invention to the embodiment illustrated. The scope of the invention will be pointed out in the appended claims.

In tuners of the character described which, as disclosed, are of the automobile type, the tuning condensers (not shown) are mounted on or at least driven from a rotatable operating shaft, a portion of which may be seen at 1 in Fig. 1 which extends out from the radio chassis

20 1a having fastening connections 1b. Fixed on this shaft is one element 2 of a friction clutch, generally designated 3, the other element 4 of which is fixed on a hollow spool 5 in turn having fixed thereon and rotatable therewith a pinion gear 6. As will presently be explained, 25 the pinion gear 6 is adapted to be manually driven for manual tuning, this drive including a driven shaft 7 having a gear 8 at one end meshing with the pinion gear and a pulley 9 at the other end.

During push button tuning, the clutch 3 is automatically disengaged as an incident to initial movement of a tuning button. The movement of a tuning button shifts an actuating plate 10 to the left as shown in Fig. 1. The plate has a lower end engageable between rims 11 and 12 on the spool 5. Release of a push button permits return of the plate 10 to the right, as shown in Fig. 1. The plate 10 causes movement of the spool 5, clutch element 4 and the associated gears 6 and 8 axially to the left, as viewed in Fig. 1. This clutch arrangement is commonly employed in the radio tuner art.

40 This clutch arrangement requires that the shaft 7 have a floating mounting. At the same time, the shaft 7 is to be biased in such a direction as to maintain tension on a belt driving the pulley 9, and this tension desirably should be and remain uniform for both directions of rotation of the shaft 7.

45 As best seen in Figs. 1 and 3, there projects from the radio chassis 1a a bracket 20 which is slotted or bifurcated to provide prongs 20a and 20b which receive the gear end of the shaft 7 slidably therein. The gear end of the shaft 7, as seen in Fig. 1, and more clearly shown in Fig. 5, has a frusto-conical projection 21 beyond the gear and bearing against this projection is a clip 22 fixed on spool 5 maintaining the gear 8 in mesh with the gear 6 and carrying that end of the shaft with the gear 6 as it and the clutch element 4 are shifted as an incident to push button tuning. The opposite end of the shaft 7 (see Figs. 4 and 5) is formed with a ball 23, the center of which is located on the center line of the pulley.

50 A shaft 24 projects forwardly through the housing for the radio and at its projecting end carries a manual tuning knob 24a, and inwardly of the housing it has fixed thereon a pulley 25. Running over this pulley and over the pulley 9 to drive the latter is an endless belt 26. Slidingly mounted for limited longitudinal movement on the center line between the upper and lower reaches of the belt 26, which coincides with the line passing through the axis of the shaft 24 and the shaft 7, is means for floatingly supporting the pulley end of the shaft 7. Herein this means is a simple, elongated, thin bar, generally designated 27. At one end this bar is bifurcated, as best seen in Fig. 2, to form lugs 27a and 27b and at that end slides over the shaft 14 with a close but sliding fit

so as to be centered on the axis of that shaft. At the opposite end, the bar 27 is formed with two laterally, inwardly projecting fingers 28 and 28a which curve around the ball 23 in a close but relatively rotatable fit. At that same end of the bar is a third finger 29 which also projects laterally inwardly and contacts the ball, this finger being spaced inwardly from the fingers 28 and 28a a distance equal to the radius of the ball 13 less one-half the thickness of the fingers 28 and 28a. Intermediate its ends the bar 27 is formed with an elongated slot 30 of major width and a shorter slot 31 of lesser width. The slot of lesser width in particular has its center line extending parallel with the center line of the belt. The slot 31 has a close but sliding fit on the shank of a bolt 32 disposed along the center line of the belt, the head of which has a diameter larger than the width of the slot to guidingly retain the bar on the bolt, but is of lesser diameter than the width of the slot 30 so that the bar may be passed over the head of the bolt by aligning the slot 30 with the bolt 32. Projecting laterally inwardly from the bar 27 at the end of the slot 30 remote from the slot 31 is a fourth finger 33 (Figs. 1 and 3) to which is anchored one end of a coil tension spring 34, the other end being anchored to a bracket 35 fixed on the radio chassis 1a and which also carries the bolt or rivet 32. The fingers 28, 28a and 29 and 33 are of such length and the point of attachment of the spring 34 to the bracket 35 is so spaced that the axis of the spring lies on and is coincident with the center line of the belt 26, as is evident in Fig. 2.

It is believed apparent from the foregoing that the bearing for the pulley end of the shaft, being substantially a ball and socket joint, permits free pivoting of the shaft 7 to accommodate the engagement and disengagement of the clutch 3 as an incident to push button tuning. At the same time the pulley end of the shaft 7 is mounted for movement along the center line of the belt 26 and through the action of the tension spring thus maintains tension on the belt. With the spring located with its axis coincident with the center line of the belt, the fact that the pulley 9 is at one time driven clockwise and at another time driven counterclockwise has no influence on the tension that is maintained on the belt because the bar 27 and the spring 34 provide no moment arm on which these forces can act differently to aid or oppose the pull of the spring.

The pulleys 40, 41, 42 and 43 and belt 44 relate to the dial mechanism for the radio and form no part of the present invention.

I claim:

1. In a radio tuner of the push-button type and having mechanism for manual tuning, in combination, a chassis adapted to support tuning mechanism, an operating shaft extending outwardly from one side of said chassis, a spool-like member loosely mounted near the outer end of said operating shaft and carrying a pinion gear, a friction clutch having one element fixed to the end of said operating shaft and another element fixed to said member and adapted to be disengaged upon push button operation, and means for manually rotating said operating shaft including a control shaft extending outwardly of said chassis in a direction generally normal to said operating shaft, a driven shaft spaced from and extending parallel to said control shaft, a gear at the driving end of said driven shaft in engagement with said pinion gear, means supporting the driving end of the driven shaft for movement with the pinion gear in a direction parallel to the operating shaft and also for movement along its length relative to the pinion gear, a driving pulley on said control shaft and a driven pulley on the driven end of said driven shaft, an endless belt rotatably interconnecting said pulleys, and means supporting said driven shaft for angular movement in response to shifting of the pinion

gear upon release of the clutch and for supporting the driven end of the drive shaft for linear movement to maintain belt tension including an elongated bar lying along the line between the axes of the control and driven shafts and having a first end bifurcated and mounted for sliding movement on said control shaft and its other end provided with socket means, the driven end of the drive shaft having a ball located on the center line of the driven pulley which is received in said socket, a headed bolt on the chassis along said line between axes, means defining a slot in said bar intermediate its ends extending lengthwise of the bar and slidably confined on the bolt, and a coil spring having its axis disposed along said line between the axes of the control and driven shafts and connected between the bar and chassis for urging the bar in a direction to maintain the belt tension.

2. In a radio tuner of the push-button type and having mechanism for manual tuning, in combination, a chassis adapted to support tuning mechanism, an operating shaft, a spool-like member loosely mounted near the outer end of said operating shaft, a disengageable friction clutch having one element fixed to said operating shaft and another element fixed to said member, and means for manually rotating said operating shaft including a control shaft extending in a direction generally normal to said operating shaft, a driven shaft having driven and driving ends spaced from and extending parallel to said control shaft and having means at its driving end to rotate said spool-like member, a driving pulley on said control shaft and a driven pulley on the driven end of said driven shaft, an endless belt rotatably interconnecting said pulleys, and means supporting said driven shaft for angular movement in response to disengagement of the clutch and for supporting the driven end of the drive shaft for linear movement to maintain belt tension including an elongated bar lying along the line between the axes of the control and driven shafts and having one end provided with socket means, the driven end of the drive shaft having a ball located on the center line of the driven pulley and which is received in said socket, means slidably mounting the bar on the chassis for movement along said line, and spring means disposed along said line for urging the bar in a direction to maintain the belt tension constant.

3. In a radio tuner of the push-button type and having mechanism for manual tuning, in combination, a chassis adapted to support tuning mechanism, an operating shaft, a spool-like member loosely mounted near the outer end of said operating shaft, a disengageable friction clutch having one element fixed to said operating shaft and another element fixed to said member, and means for manually rotating said operating shaft including a control shaft extending in a direction generally normal to said operating shaft, a driven shaft having driven and driving ends spaced from and extending parallel to said control shaft, means for rotating said spool-like member in response to rotation of the driven shaft, a driving pulley on said control shaft and a driven pulley on the driven end of said driven shaft, an endless belt rotatably interconnecting said pulleys, and means supporting said driven shaft for angular movement in response to disengagement of the clutch and for supporting the driven end of the drive shaft for linear movement to maintain tension including an elongated bar lying along the line between the axes of the control and driven shafts, a bracket fastened to the chassis, a headed guide bolt on the chassis lying along said line, said bar having a first end bifurcated and mounted for sliding movement on said control shaft and its other end provided with three laterally-extending fingers forming socket means and a slot intermediate its ends slidably retained by said headed bolt, the driven end of the drive shaft having a ball located along the axis of the driven pulley and which is received in said socket, a tension spring having its axis disposed along said line

and connected between said bracket and the bar adjacent the bifurcated end for urging the bar in a direction to space apart the pulleys and maintain the belt tension constant.

4. In a radio tuner mechanism, an operating shaft having a releasable clutch mounted at an end thereof, a driven shaft extending normal to said operating shaft having a driving end with a gear thereon and a driven end, means supporting the driving end of said shaft for limited lateral movement with one element of said releasable clutch, a pulley fixed on the driven end of said driven shaft, a reversibly rotatable control shaft extending generally parallel to and spaced from said driven shaft, a pulley fixed on said control shaft disposed in the same plane as the pulley on said first shaft, an endless belt running around said pulleys, the centerline of the belt coinciding with a line between the axes of the control and driven shaft, and means rotatably supporting the driven end of said driven shaft permitting angular movement of said shaft due to lateral displacement of the driving end thereof and movement of said driven end toward and from said control shaft to maintain said belt under tension including a bearing-forming member guiding the driven end of said driven shaft for movement only in a linear path coinciding with said centerline, and an elongated spring having its axis on said centerline biasing said driven shaft in a direction to place said belt under tension.

5. In a radio tuner mechanism, an operating shaft having a releasable clutch mounted thereon with one element fixed to the shaft and another element movable thereon, a driven shaft extending normal to said operating shaft having a driving end and a driven end, drive connections between said movable clutch element and driven shaft, means supporting the driving end of said shaft for limited lateral movement with the movable element of said releasable clutch, a pulley fixed on the driven end of said driven shaft, a reversibly rotatable control shaft extending generally parallel to and spaced from said driven shaft, a pulley fixed on said control shaft disposed in the same plane as the pulley on said first shaft, an endless driving element running around said pulleys, the centerline of the element coinciding with a line between the axes of the control and driven shaft, and means rotatably supporting the driven end of said driven shaft permitting angular movement of said shaft and movement of said driven end toward and from said control shaft to maintain said element under tension including an elongated member mounted for sliding movement along said line for guiding the driven end of said driven shaft for movement only in a linear path coinciding with said centerline, and a spring having its axis on said centerline biasing said driven shaft in a direction to place said element under tension.

6. In a belt driven mechanism, a first shaft having a driving end and a driven end, means supporting the driving end of said shaft for limited lateral movement, a pulley fixed on the driven end of said shaft, a reversibly rotatable power shaft extending generally parallel with said first shaft, a pulley fixed on said power shaft disposed in the same plane as the pulley on said first shaft, a belt running around said pulleys, and means rotatably supporting the driven end of said first shaft permitting angular movement of said first shaft due to lateral displacement of the driving end thereof and movement of said driven end toward and from said power shaft along a line extending between the axes of said first shaft and power shaft to maintain said belt under constant tension including an elongated bar having a bifurcated end slidably mounted on the power shaft, a stationary bracket, a headed bolt member mounted on said bracket to fall on said line, a slot in said bar intermediate its ends slidably confined by said headed bolt for movement along said line, three fingers on the other end of said bar forming a ball-receiving socket, a ball on the driven end of the first shaft concentric with the pulley on the first shaft.

fitted in said socket, and a coil spring extending along said centerline and connected between said bar and bracket biasing said first shaft in a direction to place said belt under tension.

5 7. In a belt driven mechanism, a driven shaft having a driving end and a driven end, means supporting the driving end of said shaft for limited lateral movement, a pulley fixed on the driven end of said shaft, a reversibly rotatable power shaft extending generally parallel with said driven shaft, a pulley fixed on said power shaft disposed in the same plane as the pulley on said driven shaft, a belt running around said pulleys, and means rotatably supporting the driven end of said driven shaft permitting angular movement of said driven shaft due to lateral displacement of the driving end thereof and movement of said driven end toward and from said power shaft to maintain said belt under tension including a bearing-forming member guiding the driven end of said driven shaft for movement only in a fixed linear path passing through the axis of said power shaft and along the centerline of said belt, and a spring extending along said centerline biasing said driven shaft in a direction to place said belt under tension.

10 8. In a belt driven mechanism, a first shaft having a driving end and a driven end, means supporting the driving end of said shaft for limited lateral movement, a pulley fixed on the driven end of said shaft, a reversibly rotatable power shaft extending generally parallel with said first shaft, a pulley fixed on said power shaft disposed in the same plane as the pulley on said first shaft, a belt running around said pulleys, and means rotatably supporting the driven end of said first shaft permitting angular movement of said shaft due to lateral displacement of the driving end thereof and movement of said driven end toward and from said power shaft to maintain said belt under tension including a bearing-forming member guiding the driven end of said first shaft for movement only in a linear path passing through the axis of said power shaft, and a spring biasing said first shaft in a direction to place said belt under tension.

15 9. In a radio tuner of the push-button type and having mechanism for manual tuning, in combination, an operating shaft, a disengageable clutch on said shaft having one element fixed to the shaft and another element movable on the shaft, a driven shaft for driving said operating shaft through the clutch, manually operable belt means for rotating the driven shaft, means mounting the driven shaft for angular movement about its driven end, means mounting the driven end of said driven shaft for limited lateral displacement in a straight line, and spring means disposed along said straight line for maintaining tension constant in said belt means.

20 10. A device of the type described in claim 9 and having, a manually operable control shaft extending parallel to the driven shaft, and a pulley on each of said control and driven shafts disposed in a common plane, said belt means running around the pulleys.

11. In a belt driven mechanism, a first shaft having a driving end and a driven end, a pulley fixed on the driven end of said shaft, a reversibly rotatable power shaft extending generally vertical with said first shaft, a pulley fixed on said power shaft disposed in the same plane as the pulley on said first shaft, a belt running around said pulleys, and means rotatably supporting the driven end of said first shaft permitting movement of said driven end toward and from said power shaft to maintain said belt under tension including an elongated bar having a bearing-forming member supporting the driven end of the first shaft, means guiding the elongated bar for sliding movement in a straight line extending between the axis of the first shaft and power shaft, and a tension spring acting on said bar to bias said first shaft in a direction to place said belt under tension.
